ELECTRICAL CORD HOLDER

Hilary P. Lodermeier, 6247 Channing Drive,
North Highlands, Calif. 95660

Filed Mar. 25, 1966, Ser. No. 1,633

Term of patent 14 years

(Cl. D54—1)

FIG-1

I claim:

The ornamental design for an electrical cord holder, as shown.
